Filed Apr. 24, 1972, Ser. No. 247,224

Term of patent 14 years

Int. Cl. D24—99; D10—99
U.S. Cl. D83—1 R

FIG. 1

FIG. 2

FIG. 1 is a front plan view of a medical indicating device showing our new design;

FIG. 2 is an edge elevational view thereof.

The device is transparent except for the markings so that a rear plan view presents the same outline and same outline for the markings.

We claim:

The ornamental design for a medical indicating device, substantially as shown and described.
